[57] CLAIM

The ornamental design for a bib for infants, invalids, or
the like, as shown and described.

DESCRIPTION

FIG. 1 is a front perspective view of a bib for infants,
invalids, or the like, showing my new design, the head
and shoulders of a figure shown in broken lines being
for illustrative purposes only, and forming no part of the
claimed design;

FIG. 2 is an enlarged top plan view thereof;

FIG. 3 is an enlarged front elevational view thereof;

FIG. 4 is an enlarged right side elevational view
thereof;

FIG. 5 is an enlarged rear elevational view thereof; and

FIG. 6 is an enlarged bottom plan view thereof.
